UNITED STATES PATENT OFFICE.

WILLIAM R. BULLOCK, OF SYRACUSE, NEW YORK, ASSIGNOR OF ONE-HALF
TO HARRY WIARD, OF SAME PLACE.

PLOW.

SPECIFICATION forming part of Letters Patent No. 244,179, dated July 12, 1881.

Application filed March 17, 1881. (No model.)

To all whom it may concern:

Be it known that I, WILLIAM R. BULLOCK, of Syracuse, Onondaga county, State of New York, have invented certain Improvements in Plows, of which the following is a specification.

Various devices have been essayed for the purpose of shifting the handles of plows from side to side for convenience in use; but in all the constructions of plows where the lower ends of the plow-handles are affixed to a brace between the mold-board and the standard or landside that have, so far as my knowledge extends, been heretofore made the range of motion has been limited too much for the purposes for which my invention is designed, and it is in this extended range of motion, and the means by which it is effected, that the novelty of my device consists. The types of the devices heretofore tried are either to slide the handles side-wise or to pivot their lower ends at a stationary point on a permanent cross-brace on which the handles turn.

My improvement consists in giving motion to the lower ends of the handles from side to side along a curved line while the handles at their upper junction with the brace-bar that sustains them are made to traverse on a curve, said curves being struck from an imaginary center at a point between the two, regulated by the range of motion desired for the handles.

The construction is as follows, referring to the accompanying drawings, in which Figure 1 is a top plan of the plow with the handles affixed. Fig. 2 is a side elevation of handles, rocker, and brace-bar. Fig. 3 is a plan of the rocker *a* and brace-bar *b*.

The plow on which my improvement is placed in the drawings is like that heretofore patented to Harry Wiard. There is a rocker, *a*, to which the lower ends of the handles are attached. This rocker is curved between the trunnions at the ends, as seen at *a*, Fig. 3, and has a curved slot through it, through which a bolt or bolts pass, uniting the lower ends of the handles to the said rocker *a*, but allowing them a lateral movement for adjustment.

The adjustable brace-bar *b*, as used in the above-named patent for raising and lowering the handles, has curved slots *b'* therein, through which the handles bolts pass to unite them together and hold them in place. The curves in the rocker *a* and in the brace-bar *b* are struck from a common center at the point *e*, Fig. 3, so located that by giving the handles free play at their lower end laterally and at the bar *b*, determined by the curved slots, as above stated, I get a large range of motion for the upper ends of the handles, with the limited space below, as indicated in Fig. 1 by dotted lines.

Having thus fully described my invention, I claim—

1. The combination of the rocker *a* and brace-bar *b*, having segmental curved slots therein corresponding to a common center between the two, substantially as and for the purposes specified.

2. In combination with a mold-board and landside of a plow, the segmental slotted rocker *a*, slotted bar *b*, and plow-handles, in the manner and for the purposes specified.

WILLIAM R. BULLOCK.
